APPARATUS FOR MOLDING PRINTING BASE MATERIAL

Filed June 1, 1949

UNITED STATES PATENT OFFICE

2,581,860

APPARATUS FOR MOLDING PRINTING
BASE MATERIALNoble A. Hunter, Capac, Mich., assignor of fifty
per cent to Myrtle M. Hunter, Capac, Mich.

Application June 1, 1949, Serial No. 96,456

1 Claim. (Cl. 22—5)

1

This invention relates to an apparatus for the casting or molding of metal bases with slots on the underside thereof for use by printing establishments, said base being adapted as a support for and upon which shell castings may be mounted and secured.

Heretofore printing establishments have casting boxes for the making of stereotype castings which are used for printing and it is the principal object of this invention to permit the utilization of the casting box for the manufacture of the base material referred to above.

It is the object of this invention to provide a plurality of bars and irons of substantially rectangular cross section which may be employed upon and within the conventional flat bed casting box to thereby define the mold into which the molten material is poured for the formation of said base material.

Heretofore the stereotype casting was solid throughout whereas it is contemplated that the slotted base material produced from the apparatus hereafter described may be substituted therefor, said base acting as a support upon which a shell casting may be mounted and secured.

It is the further object of this invention to provide the base material of the same substance from which the type is formed in a Linotype machine, so that it may be melted over when it has become worn. Furthermore, it is a great convenience to already have the right material available for the formation of said bases.

It is the further object of this invention to mold said bases at a uniform constant height whereby when the shell casting is mounted thereon the total height of said base and shell casting will exactly equal type height, i. e. the height of the row of molded type produced in the Linotype machine.

These and many other objects will be seen from the following specification and claim in conjunction with the appended drawing in which:

Figure 1 is a side elevational view of a conventional form of flat bed casting box with the cover thereof in open position.

Figure 2 is a plan view taken on line 2—2 of Figure 1 indicating the arrangement of bars and irons which are mounted upon the bed of said casting box.

Figure 3 is an elevational section taken on line 3—3 of Figure 2.

Figure 4 is a fragmentary partially broken away and sectioned perspective view of the base material molded by the present apparatus; and

Figure 5 is a fragmentary elevational section taken on line 5—5 of Figure 3.

2

It will be understood that the above drawing illustrates merely a preferred embodiment of the invention and that other embodiments are contemplated within the scope of the claim hereinafter set out.

Referring to the drawing the conventional flat bed casting box is shown in Figure 1 for producing in conjunction with the apparatus hereafter set out, the base material in the form shown in Figure 4.

Said base material generally indicated at 11 in Figure 4 is substantially rectangular in shape and includes the platform 12 and the outer parallel spaced end portions 13 and 14. Interposed between the members 13 and 14 are a plurality of upright parallel spaced supporting legs 15 which are reinforced at their bases by the webbing 16 and 17 shown in Figure 4. There may be transverse openings 18 formed in the platform 12 between each of the legs 15 in view of the spacer pins 49 hereafter described in connection with the casting bars 47.

Referring now to Figure 1 the casting box includes the base portion 19 and the upright 20 at one end which terminates in the bifurcated portion 22. It will be noted that the casting box referred to includes a second base portion 19 which is identical in shape to the one shown in Figure 1 and which is secured in spaced relation thereto as by the spacer bar 21, the end of which is shown in Figure 1 as well as by the cross bar 37 hereafter described.

The specific construction of the flat bed casting box forms no part of the present invention and consequently the details of its construction are omitted.

The casting box however, has a rectangularly shaped flat bed 24 and a pair of trunnion shafts 23 project from opposite sides thereof being pivotally mounted within and between the bifurcated portions 22 shown in Figure 1 whereby said bed may be pivoted to a vertical position when desired for the casting operation.

The opposite end 25 of the bed 24 is supported within the notch 26 at the upper end of the release latch 26 which is pivotally mounted at 27 to the base 19. The arm 28 is suitably secured at one end to the shaft 27 and its opposite end is pivotally joined at 29 to the upright link 30 whose lower end is pivotally joined at 31 to the treadle 32. The latter is pivotally mounted to the base 19 at point 33, while its forward end 35 is provided with a foot piece 34 for actuating said treadle.

It is apparent that manual application of the treadle 32 will effect a clockwise pivotal movement of the release 26 so that the bed 24 will automatically pivot downwardly into a vertical

position within and between the base members 19 of the casting box. The treadle arrangement also forms a part of the conventional casting box and operates in a conventional manner to permit the automatic pivotal movement of the bed 24 and its cover 38 to a vertical position.

The base 19 also includes the uprights 36 at the end thereof which are joined by the spacer 37, the latter being adapted to support the flat cover 38 when tilted to the position shown in Figure 1. In normal casting operations the cover 38 which is hinged at 39 and which includes an adjustable connection 40, is adapted to assume the dotted line horizontal position shown in Figure 1. It will be noted that both the flat bed 24 and the cover 38 have a tapered portion 39 so that when said cover is closed said tapered portions will cooperate to provide a throat or pouring opening for the molten material used when the cover and the bed 24 have been together pivoted to a vertical position.

The irons and casting bars hereafter described are first mounted and positioned upon the bed 24 in the manner shown in Figure 2 after which the cover 38 is closed to the dotted line position shown in Figure 1. A plurality of brackets 49 are secured to the opposite edges of the bed 24 and suitable clamps 41 with securing screws 42 are pivotally mounted upon said brackets whereby the cover 38 may be effectively secured in closed position before said bed and cover are permitted to tilt to the vertical casting position.

However, again referring to Figures 1 and 2, before the cover is closed, the end iron 44 of substantially rectangular cross section is positioned loosely upon the bed 24, said end iron including a plurality of transverse spaced notches with vertical walls 45 and bottom walls 46.

There are a plurality of casting bars 47 of substantially rectangular cross section but which have a slight downward taper at 52, and these bars are arranged substantially parallel to each other with their ends nested and projected within the slots 45-46 in the manner shown in Figures 2 and 3. It will be noted that the heights of the casting bars 47 are such that the upper edges thereof are flush with the top surface of the end iron 44.

The opposite ends of casting bars 47 are formed with the downwardly depending legs 48 which bear upon the bed 24 and thereby establish a parallel spaced relation between the top of the bed 24 and the under surfaces of each of the casting bars 47 to provide for the formation of the platform 12 of the base to be molded in applicant's apparatus.

A plurality of spacer pins 49 having a slight downward taper to permit easy removal from the cast base are secured to and downwardly depend from the under surface of said casting bars with the lower ends of said pins cooperatively engaging the top surface of bed 24 to prevent any possible bending of the casting bars 47 during the molding operation.

It will be noted as shown in Figure 3 that each of said casting bars 47 have a plurality of longitudinally spaced undercut upwardly converging notches 50 formed in the under-surfaces thereof to permit entry of the molding material to form the transverse reinforcing webbing 16 shown in Figure 4.

Furthermore if desired a secondary group of spaced transverse upwardly converging notches 51 may also be formed within the under surface of the casting bar 47 to provide for the transverse reinforcing webbing 17 shown in Figure 4.

Heretofore such reinforcing wasn't necessary as the stereotype base material was usually solid. As one of the objects of the present invention was to provide an apparatus which would produce a light slotted base material, it has been found necessary to provide for the reinforcing webbing 16 and the additional webbing 17 if desired.

It is apparent that if the spacers 49 are employed there will be small openings 18 in the molded base such as shown in Figure 4. It will be noted as shown in Figure 5 that the casting bars 47 have slightly tapered side portions 52 to facilitate removal thereof from the cast base 11 i. e. from between the cast legs 15.

Again referring to Figure 2 the apparatus for casting the base material 11 is completed by employing the spaced side irons 43 which are substantially rectangular in cross-section and which are arranged at right angles to the end iron 44 and are positioned upon the bed 24 with their one ends snugly engaging the inner wall of said end iron 44 as shown in Figure 2.

Thus, the mold for forming the base material 11 shown in Figure 4 is completed as shown in Figures 2 and 5 by employing the plurality of casting bars 47 in association with the notched end iron 44 and the parallel spaced outer side irons 43, all of which are loosely mounted upon the flat bed 24 after which the cover 38 is pivoted to the dotted line horizontal position shown in Figure 1, and is suitably and securely clamped by the clamps 41.

It is to be noted that so assembled the bars 47 as well as the irons 43 and 44 are of exactly the same height so that there is a tight registry of the under surface of the cover 38 with the top surfaces of each of said bars and irons. After the clamps 41 have been tightly secured by the bolts 42 and the cover 38 is effectively held down, the treadle 35 is manually actuated releasing the bed 24 and the same will pivot to a vertical position for the pouring of the molded material into the throated portion 39 above described.

After this operation and after the material has hardened the bed 24 is again pivoted into the horizontal position shown in Figure 1 and the cover 38 is lifted as shown. The casting bars 47 are manually withdrawn from the molded base 11 and the base itself may be manually lifted from the bed 24. Said base will be of the formation shown in Figure 4 and may be easily sawed to the correct length for any particular intended use. The side walls 13 and 14 may also be easily sawed if desired to obtain the correct column width. Because of the material employed which is relatively soft, it is comparatively simple to saw the base material to the proper length.

It is contemplated that the number and spacing of the upright legs 15 of the base material 11 could be variable however, it has been found that it is advisable for the printer to establish a particular arrangement such as shown in Figure 2 for illustration, and to stick by this arrangement to thereby always obtain uniformity in the mold bases which are cast.

The base produced by the apparatus above described will always be of a uniform height so that when the shell casting is positioned and secured to the top surface of the platform 12 of said base such as by double coated scotch tape, the assembly will be of exactly the correct or type height, and it will not be necessary to use a planing machine as was often the case where the solid stereotype was employed.

Heretofore in the formation of the stereotype which included a solid base, the weight of the metal poured was such as to cause some bending of the paper matrix which is normally employed in the formation of the stereotype casting, and which is also employed in the formation of shell castings. In producing the solid stereotype casting due to such bending, there would be certain high spots in the casting which had to be removed by a routing machine. By employing merely shell castings with a minimum weight of metal, the matrix does not bend, there are no high spots and the use of a routing machine is obviated. It is apparent also that in molding the shell casting considerably less backing of the matrix is needed.

It is apparent that by employing the slotted base material above described as a support for shell castings, the excessive weight of the stereotype solid casting is eliminated and consequently the total weight of the completed printing form is minimized.

It is apparent further that the molded base material 11 is versatile in its use and may be sawed to any desired length readily. Said base material may be used in rearranging the make-up of the printing form or chase and may be used for holding the column rules in place.

By employing the base material described it is possible to have a pre-assembly of the base in the printing form of the size and of the arrangement which may have been reserved and upon which there will be mounted a particular shell casting. In other words, the frame may be to this extent completely made up and the shell castings later mounted and secured upon the base material when they are received or obtained.

Heretofore if there was any warping of the solid type casting it was necessary to unlock the whole chase or frame and introduce shims to correct the same.

By employing the base material described and using a shell casting thereon, it is not necessary to unlock the frame, and any warping which may have occurred can be corrected merely by inserting a paper shim directly under the shell casting at the proper place.

It will be understood further that the base material provided may be used over and over again and may be stored for use as and when desired.

The procedure in the use of the casting bars for the making of printers light weight base for mounting shell castings, or for use as basing material is as follows:

With the casting box open casting paper is first placed on the bed 24. Next the end iron 44 is placed in position crosswise of the bed with the open slots 45—46 which receive the ends of the bars 47 facing towards the pouring end of the box and up.

The small ends of the bars 47 are next placed in the slots of the end iron 44 with the leg ends 48 thereof being arranged toward the metal pouring end or open end of the casting box and down. The leg ends of the bars 47 are next spaced equal distances apart, and a spacing gauge may be used for this purpose if desired.

After this the side irons 43 are arranged on each side of the bars 47 and at a suitable distance therefrom to provide for ample thickness of the outside legs or members 13 and 14 of base 11.

A sheet of casting box paper is then placed on top of this assembly and the cover 38 is closed to the horizontal position shown in Figure 1 and is securely clamped in position. After this the

casting box is tilted to an upright position and the metal is poured thereinto in any convenient manner.

5 The casting box is then arranged into a horizontal position, the cover 38 raised and the casting removed, separated from the bars and irons and is saw-trimmed to the desired printers measure.

10 It will be noted that the base material may be of the same substance from which the type is formed in a Linotype machine, or on the other hand stereotype, Monotype or Intertype metals may be employed for this purpose. It is possible also that foundry type metal could be used if it is desired to obtain an extra hard cast base.

15 Having described my invention, reference should now be had to the claim which follows for determining the scope thereof.

I claim:

- 20 A casting box comprising a flat bed, a cover pivotally mounted at one end upon said bed, an end iron of rectangular cross-section positioned upon said bed and having a plurality of spaced lateral notches in its side surface, a plurality of 25 parallel spaced casting bars of rectangular cross section arranged at right angles to said end iron with their one ends nested and supported within said notches, depending legs on the opposite ends of said bars extending below said one ends and bearing upon said bed defining a longitudinal slot between said bed and the under sides of 30 said bars, a pair of spaced side irons of rectangular cross-section positioned on said bed with their one ends engaging said end iron and arranged 35 in parallel spaced relation to the outer of said casting bars, the top surfaces of said end iron, casting bars and side irons being coplanar, said cover being secured in compressive registry with the top surface of said end iron and the top surfaces 40 of said side irons and said bars, and parallel to said bed for maintaining an assembled relation between said bed, irons, and bars, said end iron and side irons forming respectively one end wall and the side walls of said casting box, 45 the under surfaces of said casting bars having formed therein a plurality of transverse longitudinally spaced upwardly converging slots of different heights, whereby the molded article will be formed with a plurality of transverse reinforcing webbing of corresponding different 50 heights, one end of said box being open to permit the introduction of molten material therein.

NOBLE A. HUNTER.
